HAIR CURLER

Jacob Goodman, Brooklyn, N. Y., assignor to
Delamere Company, Inc., a corporation of
Delaware

Application July 5, 1935, Serial No. 29,840

5 Claims. (Cl. 132—31)

This invention relates to a hair curler, and has among its objects to provide a sleeve about which the hair may be wound or rolled and which may be retained in the hair until the hair has been set in curl, and to provide a separable device for rolling the sleeve to wind the hair thereon and for temporarily clamping the ends of a lock of hair on the sleeve during the rolling operation.

10 The sleeve member of my invention comprises a tube of rubber or like soft pliable material, and it is provided with a locking member, either separate or attached, whereby the sleeve may be retained in place in the hair after the hair has been wound thereon. The sleeve is constructed of flexible material and may be worn comfortably, even during sleep. In this respect, my invention marks a definite advantage and improvement over the types of curlers made of metal or other rigid material, or those having wire fasteners or locking devices, as curlers of such type cannot be worn without discomfort while sleeping.

15 The curler is inexpensive to manufacture and may be marketed as a unit consisting of one rolling device and a plurality of sleeve members. Any number of sleeve members may be used interchangeably with a single rolling device. This results in an economy for the purchaser and 20 permits the user to form a number of curls with one device.

25 Other advantages of the invention will appear from the following description thereof, reference being had to the accompanying drawings, in 30 which:—

Figure 1 is a cross-sectional view of the sleeve member of my improved hair curler;

Fig. 2 is a side elevation of the curler, partly in section, showing the sleeve positioned on the 40 rolling member and the clamp opened;

Fig. 3 is a top plan view of the curler showing ends of a lock of hair clamped on the sleeve;

Fig. 4 is a side elevation of the curler having a lock of hair wound about and fastened on the 45 sleeve;

Fig. 5 is a perspective view of a detached sleeve with a lock of hair wound and fastened thereon;

Fig. 6 is a bottom view of the rolling member showing a modified form of sleeve thereon;

Fig. 7 is a detailed view of an end portion of the rolling member;

Fig. 8 is an exploded view showing a modified form of the rolling member, sleeve, and locking member;

Fig. 9 is a side view, partly in section, of the above elements combined; and

Fig. 10 is a bottom view of the rolling member shown in Fig. 8.

The sleeve member 10 of my curler is in the form of a hollow tube having a bore 11. The sleeve is made of a soft pliable material, preferably rubber, and is provided with a locking member or elastic cord 12 extending outwardly from one end. The cord 12 may be made integral 10 with the sleeve or as a separate part suitably connected thereto. The free end of the cord is formed or provided with a plug or tip 13. If desired, the wall of the sleeve may be perforated to provide for circulation of air. I have found 15 that a satisfactory way of making the sleeve is to mold it together with the cord and plug of a single piece of rubber. It is to be understood, however, that I do not limit myself to such construction, and that the plug may be made of or reinforced with metal.

20 After the hair is rolled on the sleeve, the cord 12 is stretched longitudinally over the hair, and the plug 13 is inserted into the opposite open end of the sleeve to lock the cord and to hold the 25 hair wound on the sleeve. The inner end of the plug 13 may have a flange or disk 14 which abuts against the end of the sleeve and provides a means for conveniently withdrawing the plug when it is desired to remove the sleeve after the 30 hair has been curled.

The rolling device comprises an arm 15 which may be cylindrical, semi-cylindrical, or any other suitable form adapted for insertion into the bore 11 of the sleeve, to hold the sleeve in place, and a clamping arm 16 pivotally connected at 17 to the arm 15. The rolling device may be provided with the usual spring, not shown, for urging the arm 16 down against the sleeve.

35 In using the device, the sleeve 10 is placed on the arm 15 with the cord extending rearwardly, as shown in Fig. 2. The ends of a lock of hair 18 are then clamped on the sleeve and the device is rotated to roll the hair upon the sleeve. After 40 the desired length of hair has been rolled, the cord 12 is extended over the hair and locked in place by inserting the plug into the open end of the sleeve, whereupon the rolling device may be withdrawn from the sleeve, leaving the sleeve in 45 place with the hair rolled and fastened thereon.

50 In the modified form of the device shown in Fig. 6, the sleeve 10 is provided with an elastic band 19 having a tip 20 at its free end and having its opposite end suitably fastened to the sleeve, as, for example, by means of the staple 21.

The handle end of arm 25 of the rolling member is formed with a notch 22 having a constricted opening 23. The free end of the band 19 may be caught in the notch to hold the band out of the way while the hair is being rolled. After the hair has been wound on the sleeve, the free end of the band is inserted in the open end of the sleeve to lock the roll of hair in place.

A further modification is shown in Figs. 8, 9 and 10, in which the rolling member comprises a rolling arm 25 and a clamping arm 26 pivotally connected at 27. The arm 25 has a concave groove 28 extending from the handle portion to the end. The elastic cord or band 19, in this instance, is free from physical attachment to the sleeve 10 and is provided with a tip 20 at each end.

In using this form of device, the hair is wound on the sleeve 10 and, while the sleeve is still supported on the arm 25 of the rolling member, one end of the band 19 is inserted in one end of the sleeve, and the other end of the band in the opposite end of the sleeve, as indicated by the dotted lines in Fig. 9. The groove 28 in the arm 25 facilitates entrance of the tips 20 into the bore of the sleeve. When the ends of the band are inserted in the sleeve, and the rolling member is withdrawn from the sleeve, the band 19 will hold the sleeve in the hair with the hair wound thereon.

Having now described my invention and the manner in which it is used, I wish to have it understood that I do not limit myself to the precise arrangement of parts and details of construction set forth, as the same may be modified in various respects without departing from the scope of the invention.

What I claim is:

1. A hair curler comprising, in combination, 40 a flexible tubular sleeve of soft material about which the hair may be wound, an elastic cord extending outwardly from one end of the sleeve and having its free end adapted to be inserted into the opposite end of the sleeve, and a separable rolling arm adapted to be inserted into and to support the sleeve throughout substan-

ti ally its entire length for rotating the latter to wind the hair and to be separated from the sleeve after the hair has been wound thereon.

2. A hair curler comprising, in combination, a flexible tubular sleeve of soft material about 5 which hair may be wound, means connectable to the sleeve for holding the hair wound thereon, a separable rolling arm adapted to support the sleeve throughout substantially its entire length for rotating the latter to wind the hair thereon, 10 and a clamping arm pivotally connected to the rolling arm for clamping ends of the hair on the sleeve during the rolling thereof.

3. A hair curler comprising, in combination, a flexible tubular sleeve of soft material about 15 which hair may be wound, an elastic cord attachable to the sleeve for holding the hair wound thereon, a separable rolling arm adapted to support the sleeve throughout substantially its entire length for rotating the latter to wind the 20 hair thereon, and a clamping arm pivotally connected to the rolling arm for clamping ends of the hair on the sleeve during the rolling thereof.

4. A hair curler comprising, in combination, a flexible tubular sleeve of soft material about 25 which the hair may be wound, an elastic cord extending outwardly from one end of the sleeve and having its free end adapted to be inserted into the opposite end of the sleeve, a separable rolling arm adapted to be inserted into and to 30 support the sleeve throughout substantially its entire length for rotating the latter to wind the hair and to be separated from the sleeve after the hair has been wound thereon, and a clamping arm pivotally connected to the rolling arm 35 for clamping ends of the hair on the sleeve during the rolling thereof.

5. In a hair curler of the character described, a tubular rubber sleeve having an elastic cord extending outwardly from one end thereof and 40 adapted to extend lengthwise over the sleeve substantially parallel to the longitudinal axis thereof, said cord having a tip at its free end for insertion into the opposite end of the sleeve.

JACOB GOODMAN.
